WALLPAPER REMOVER

Maxey C. Cooper, Detroit, Mich.

Application May 1, 1935, Serial No. 19,173

10 Claims. (Cl. 216—8)

- My invention relates to apparatus for removing wall paper from the surface to which it is applied. It is an object of the invention to provide a portable device for distributing water over the surface of the paper and applying heat directly thereto so as to cause the water to penetrate the paper and loosen the paste holding the paper to the surface to which it is applied whereby it may be easily and quickly removed with a knife in the usual manner.
- 10 A further object of the invention is to provide a heating plate adapted to be moved over the surface of the paper to be removed and means for distributing water between the plate and paper, the plate having means for confining the water within the area of the plate.
- 15 Another object of the invention is to provide a device of the above-mentioned character which is simple and durable in construction, reliable and efficient in use and inexpensive to manufacture.
- 20 Other objects and advantages of the invention will be apparent during the course of the following description.
- 25 In the accompanying drawing, forming a part of this specification and in which like numerals are employed to designate like parts throughout the same.
- Fig. 1 is a vertical sectional view of the device, 30 Fig. 2 is a front elevation of the same, Fig. 3 is a horizontal section taken on line 3—3 of Fig. 2, and, Fig. 4 is a horizontal section taken on line 4—4 of Fig. 2.
- 35 In the drawing, wherein for the purpose of illustration, I have shown a preferred embodiment of my invention, the numeral 5 denotes a heating plate of substantially rectangular shape having a heating unit 6 attached to the back thereof which is enclosed in the housing 7. A bracket 8 is attached to the center of the back of the housing 7 which supports the vertical handle 9 by means of which the device is grasped in the hand. A wire 10 connects the unit 6 with a control switch 11 mounted on the bracket 8, which in turn is connected by the wire 12 to a source of electric current.
- 40 A water distributing chamber 13 is mounted above the upper edge of the heating plate 5 and is spaced therefrom by insulation or air 14. The
- chamber extends transversely of the plate, the front of the chamber being open and covered with a flexible cover 15 secured thereto by the frame 16. A plurality of coil springs 17 are disposed within the chamber between the back thereof and the cover 15 which cause the cover to bulge outwardly beyond the face of the plate 5 and conform to the surface with which it is brought into contact. The bulged out portion of the cover is provided with a row of spaced openings 18 which distribute the water from the chamber onto the surface of the wall. The upper portion of the face of the plate 5 has a series of spaced vertical grooves 19, so that as the plate is moved over the wet surface of the paper, the ribs between the grooves will gradually heat the wetted paper and at the same time the water is trapped in the grooves to produce a scalding effect on the paper.
- 45 The water is admitted into the chamber 13 by the needle valve 20 connected to the back of the chamber and communicating therewith. Disposed beneath the needle valve is the main control valve 21 connected with the needle valve by the pipe 22. The stem 23 of the valve 21 extends through the plate 5 and has a head 24 on its outer end adapted to contact with the surface against which the plate 5 is placed. A coil spring 25 mounted on the valve stem 23 between the body of the valve and the washer 26 normally holds the valve in closed position, but upon contact of the head 24 with the wall, the stem 23 is pushed inwardly opening the valve 21. The valve 21 is connected with a tank of water 27 under pressure, or any other suitable water supply, by the conduit 28 which passes through the center of the handle 9.
- Extending along the side and bottom edges of the plate 5 are channel members 29 adapted to receive flexible strips of suitable packing material 30. The flexible strips are retained in the channel members by a series of pins 31 having one end embedded in the strips and their opposite ends extending through openings in the bottom of the channels and equipped with heads 32 which limit the movement of the pins and retain the strips in place. Coil springs 33 are mounted on the pins 31 between the bottom of the channels and the washers 34 mounted on the pins, which force the strips outwardly and cause them to con-

form with the surface of the wall with which they come in contact, thereby confining the water within the area of the heating plate.

In operation, the device is applied to the surface of the wallpaper to be removed and upon contact of the heating plate 5 with the surface, the head 24 of the valve stem 23 is forced inwardly against the tension of the spring 25, opening the valve 21, so as to permit water to flow through the needle valve 20 into the chamber 13 from which it is discharged through the openings 18 onto the surface of the paper. As the plate 5 is moved over the wetted surface the ribs between the grooves 19 gradually heat the wetted paper and the water is trapped in the grooves which produce a scalding effect that loosens the old paste instantly, so that it may be removed with a knife in the usual manner. The packing strips 30 which surround the side and bottom edges of the plate 5 confine the water within the area of the plate.

It is to be understood that the form of my invention herewith shown and described is to be taken as a preferred example of the same and that certain changes in the shape, size and arrangement of the parts may be made without departing from the spirit of the invention or scope of the subjoined claims.

Having thus described my invention, I claim:

1. A device of the character described comprising a heating plate, a water distributing chamber disposed above said plate and having discharge openings, means in the working face of the heating plate for trapping water passing downwardly from said chamber, and means around said plate for confining the water within the area defined by the plate.

2. A device of the character described comprising a heating plate, a water distributing chamber disposed above said plate, a flexible cover for said chamber having a series of discharge openings, spring means for forcing said cover outwardly, packing strips along the sides and bottom edges of said heating plate, and means forcing said strips outwardly against the surface to which said plate is applied.

3. A device of the character described comprising a plate, a heating unit attached to the back of said plate for heating the same, a water distributing chamber above said plate, a flexible cover for said chamber having a series of discharge openings, grooves formed in the upper portion of the face of said plate for trapping water, and means around said plate for confining the water within the area defined by the plate.

4. A device of the character described comprising a plate, a heating unit attached to the back of said plate for heating the same, a water distributing chamber above said plate, a flexible cover for said chamber having a series of discharge openings, grooves formed in the upper portion of the face of said plate for trapping water, means for connecting a water conduit with said chamber, a control valve in said means having its stem projecting through said plate adapted to contact with the surface against which the plate is applied to actuate said valve, and means around said plate for confining the water within the area of the plate.

5. A wall paper removing device consisting of a frame provided with a water retarding element along its lower edge and its opposite vertical edges and providing a chamber bounded by said

edges, a heating plate carried by said frame, an electrical heater for heating said plate, a water distributor located above said plate and provided with a series of jet openings through which water may be discharged against the surface of a wall engaged by said water retarding elements, means for controlling the flow of water through said distributor, and means for supplying water to said distributor.

6. A device of the character described, comprising a plate body having a face adapted for contact with a wall, yieldable elongated bodies bordering two sides of the plate and one end thereof, resilient means normally urging said bodies to extend throughout their lengths beyond the said face of the plate, means providing a water chamber across the other end of said plate, said chamber having a wall provided with water outlet apertures whereby water escaping therefrom will flow downwardly across the said face of the plate, means in the face of the plate for trapping the water flowing downwardly thereover, and means for heating said plate.

7. A device of the character described, comprising a plate body having a face designed for application to a wall surface, means forming a channel along each of two opposite sides of the plate and along an end thereof, a strip of yieldable material lying in and extending throughout the length of each of said channels, yieldable means within the channels normally urging said strips of material outwardly, means facilitating the discharge of water across the other end of said plate to flow downwardly over the said face of the plate when the latter is in use, and means for heating said plate whereby the water passing thereover will be converted into steam.

8. A device of the character described, comprising a plate body having a face designed for application to a wall surface, means forming a channel along each of two opposite sides of the plate and along an end thereof, a strip of yieldable material lying in and extending throughout the length of each of said channels, yieldable means within the channels normally urging said strips of material outwardly, means forming a water receiving chamber across the other end of the plate, a yieldable wall for one side of said chamber between the side ones of said strips of material, said wall having water outlet apertures therein, yieldable means normally urging said wall outwardly to the plane in which the outer faces of said strips of material lie, said plane being parallel with and in front of the wall engaging face of said plate, and means for heating the plate whereby water discharged from said wall apertures and flowing downwardly over the face of the plate will be converted into steam.

9. A device of the character described, comprising a plate body having a face designed for application to a wall surface, means forming a channel along each of two opposite sides of the plate and along an end thereof, a strip of yieldable material lying in and extending throughout the length of each of said channels, yieldable means within the channels normally urging said strips of material outwardly, means forming a water receiving chamber across the other end of the plate, a yieldable wall for one side of said chamber between the side ones of said strips of material, said wall having water outlet apertures therein, yieldable means normally urging said wall outwardly to the plane in which the outer faces of said strips of material lie, said plane being parallel with and in front of the wall engag-

ing face of said plate, means for heating the plate whereby water discharged from said wall apertures and flowing downwardly over the face of the plate will be converted into steam, and a plurality of water entrapping channels formed vertically of the face of said plate adjacent the upper portion thereof.

5 10. A device of the character described, comprising a heating plate having a face designed for application directly to the surface of a wall,

means for discharging water at the top edge of said plate and on a line extending substantially the full width of the plate, to flow downwardly over the wall engaging face thereof, and means in the face of said plate adjacent said top edge 5 for trapping the water flowing thereover, said means constituting grooves extending vertically of the plate and of gradually decreasing depth downwardly.
